CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

CIRCUIT BREAKER.

Application filed July 17, 1925. Serial No. 44,302.

My invention relates to circuit breakers, and particularly to a circuit breaker which is both manually and thermostatically operated to open the circuit controlled thereby. 5 Among the objects of my invention are, first, to reduce the mechanical stress imposed upon the thermostatic element; second, to so arrange the mechanism that such stress as is imposed upon the thermostatic element places the latter under tension rather than under compression; third, to provide means for resetting the thermostatic trip mechanism while the circuit is open; fourth, to provide a simple and efficient general layout of the circuit breaker for accomplishing my objects above stated; and fifth, various features of detail hereinafter described or shown in the accompanying drawings, in which—

Fig. 1 is a plan view of a circuit breaker 20 in which my invention is embodied in one form;

Fig. 2 is a similar view showing the position of the parts on automatic opening of the circuit;

Figs. 3 and 4 are sections on the lines 3—3 and 4—4, Fig. 1, respectively.

In circuit breakers of the type to which this invention relates, it has been proposed to provide a circuit-opening mechanism 30 which comprises a thermostatic element. In the prior construction the thermostatic element, in its normal position, directly supports a member which is subjected to heavy stress by the operating spring of the circuit breaker mechanism. This is objectionable, since the thermostat may soften somewhat under the heating action of overload current, and the pressure exerted thereon tends to buckle the element. A permanent

40 set results which interferes with the proper functioning of the element. Moreover, the normal warping of the thermostat which withdraws it from supporting position, must be effected against the frictional drag 45 imposed upon the parts under the stress of the circuit breaker spring. This frictional drag brakes the operation of the thermostatic element, necessitates heavier overload to warp it, and consequently increases the 50 danger of overloading and buckling.

By my invention I not only change the effort exerted upon the thermostatic element from a compression effort to a tension effort, but I greatly reduce the braking effort. To

effect these results I provide between the 55 thermostatic element and the circuit breaker mechanism a trip device so located and interposed between these parts that the stress exerted upon the thermostatic element is not only minimized, but also exerted in a direction to tension the same. The mechanism is thus rendered far more sensitive to overload, and the danger of imparting a permanent abnormal set to the thermostatic element is eliminated.

Referring to the drawings, I have illustrated my invention in a circuit breaker of the general type shown in the patent to myself and one William H. Keefe, Jr., No. 1,656,851, dated January 17, 1928, and in the 70 copending application by myself and one William H. Keefe, Jr., Ser. No. 45,834 filed July 24, 1925, pertaining to certain features of the mechanism other than those to which my sole invention is directed. The circuit 75 breaker, as here shown, comprises a base 15 of insulating material, upon which is mounted a cover 16 with insulating lining 17, to house in the thermostat and the circuit breaker mechanism. Line terminals 18 and 19 project beyond the switch base and are respectively connected to the housed stationary switch contacts 20 and 21 through intermediate conductors, as hereinafter explained in detail. The circuit-closing block 80 22 which is adapted to bridge the contacts 20 and 21, is mounted on a rock lever 23 pivoted at 24 (Fig. 2) in the crotch of the V-shaped frame 25, and playing between the opposite sides of the V-opening. The frame 90 25 is pivoted at 26 in the stationary bracket 27 secured in any suitable manner to the base 15.

Cooperating with the rock lever 23 is a yoke member 28 pivoted at 29 (Fig. 3) on 95 the bracket 27 and connected by a pull spring 30 to the rock lever. A spindle 31, secured to the yoke 28, projects through the cover 16 and carries the operating thumb piece 32. Upon manual oscillation of the 100 latter the yoke 28 is swung on its axis, thus causing the attached end of spring 30 to shift from one side to the other of the pivot 24 of the rock lever 23, and thus exert its stress in a direction to throw the rock lever 105 across the V-opening in the frame 25 to open or close the circuit in a manner well understood in the art.

The switch frame 25, as above stated, is pivoted at 26. Under normal conditions it is supported in fixed position by a lug 33 which rests upon the shoulder 34 of trip lever 35. The latter is pivoted at 36 adjacent the shoulder 34, while its opposite end is engaged by the catch 37 mounted at the free end of the U-shaped thermostatic element 38. Inasmuch as the yoke 28 is mounted upon the fixed bracket 27, the operating spring 30 constantly exerts, through the rock lever 23, an effort upon the pivoted frame 25, causing the lug 33 to bear upon the trip lever shoulder 34 and thus stressing the latter in a direction to cause the free end of the trip lever to bear against the catch 37 of the thermostat 38. The effort thus exerted upon the thermostatic element places the latter under tension. Moreover, the stress exerted upon the thermostat through the trip lever 35 is very slight, by reason of the fact that the frame supporting shoulder 34 is adjacent the pivot 36, and the distance therefrom to its free end, which engages the catch 37, is many times greater than the distance between the shoulder 34 and the pivot point 36. The trip lever is thus a lever of the third class, in which the power is applied close to the fulcrum point, and the effective effort of which at the distant point of load, is very slight. Consequently, the frictional braking effort exerted by the trip lever upon the catch 37, upon the warping displacement of the thermostatic element is reduced to a minimum. Since the operation of the thermostat is thereby rendered very sensitive, danger of overheating is very slight, and even if overheating should occur, the mechanical stress on the thermostat is not only slight but also in tension. No permanent set in buckled condition can occur and the danger of deformation by elongation is practically nil.

The position of the parts when the thermostatic element has been warped out of normal position by current overload, is indicated in Fig. 2. The warping of the thermostat withdraws the catch 37 from the end of the trip lever 35, and the latter now disengaged at its free end, swings away from the thermostat under the effort of the spring 30 exerted through the frame lug 33 against the shoulder 34. The lug 33 escapes the shoulder and the frame swings on its pivot, under the stress of spring 30, until halted by the stop lug 39. In this position the circuit is opened by the combined action of the swinging frame 25, which positively forces the rock lever out of circuit-closing position, and further by the throw of the rock lever across the V-opening of the frame 25. The shift of the pivot point 24 of the rock lever across the plane of effort of the spring 30 causes the spring to swing the yoke 26 toward its open-circuit position. The yoke is halted, however, in intermediate position

by the stop lug 40 on the frame 25, so that the handle 32 which moves with the yoke occupies an intermediate indicating position, as set forth in the copending joint applications above mentioned. 70

To return the parts to normal position, the thumb piece 32 is moved to the position which it occupies when manually operated to open-circuit position. This causes the yoke 28 to swing to the left (Fig. 2), carrying with it the frame 25 and causing the lug 33 thereof to engage the nose 41 of the trip lever 35. The latter is thereby forced to return to normal position, and if the thermostat 38 has sufficiently cooled and straightened out again, the free end of the trip lever displaces the catch 37, moves past it and is again engaged in the position shown in Fig. 1 when the thumb piece 32 is released so that the effort of the spring 30 is again exerted through the lug 33 of the frame upon the shoulder 34 of the trip. 80

The circuit connection between the terminal 18 and the contact 20 is traced as follows: from the inner end of the terminal 18, through screw bolt 42 to bracket 43 (Fig. 4), through leg *a* of the U-shaped thermostat to leg *b* of the thermostat, thence through bridge 44, through screw 45, shunt 46 and screw 47 to contact 20. The circuit from terminal 19 follows a course through screw 48 to the base of contact 21. 90

Such and other modified arrangements will doubtless occur to those dealing with the problem, which nevertheless embody the underlying thoughts which I claim as my invention. 100

It will of course be obvious that the single trip lever may be replaced by a group of multiplying levers but this complication I have found unnecessary and undesirable. Again it will be recognized that by reducing in some such fashion as indicated, the effort exerted by the circuit breaker spring upon the thermostat, the mechanical load on the latter may be so far eliminated that the effort may be exerted thereon in compression rather than in tension, without reducing its sensitivity to overload current or causing the element to buckle when softened by heat. 110

I claim—

1. A circuit breaker mechanism including a movable member, a spring stressing same constantly to open-circuit position, a swinging support for said movable member, and a warping thermostatic element operatively engaged under tension by said support when the parts are in normal position, but automatically releasing the support on overload to permit its displacement by the movable member under the stress of said spring. 120

2. A circuit breaker mechanism comprising a movable member, a spring stressing the same constantly to open-circuit position, a warping thermostatic element and a stress- 130

minimizing swinging support for said movable member operatively engaging the thermostatic element under tension when the parts are in normal position, but automatically swinging out of supporting position when released by the thermostat on overload.

3. A circuit breaker mechanism comprising a movable member, a spring stressing the same constantly to open-circuit position, a warping thermostatic element and a stress minimizing swinging support for said movable member operatively engaging the thermostatic element under tension when the parts are in normal position, but automatically swinging out of supporting position when released by the thermostat on overload, said stress-minimizing swinging support engaging the thermostatic element under stress lower than that imposed upon the support by the movable member under the action of said spring.

4. In a circuit breaker, a spring stressed member, a pivoted trip device normally supporting said pivoted member against the effort of its associated spring, an overload device normally maintaining said trip device in position to support said pivoted member but freeing the latter on over load to permit the displacement of said pivoted trip device under the effort of said spring-stressed member and manually operated means for restoring said trip device and pivoted member to normal position.

5. In a circuit breaker, a pivoted frame,

a manually operated circuit opener pivoted thereon, a spring stressing said circuit opener against the frame, a displaceable member normally supporting the frame, and a thermostat normally engaging said displaceable member but freeing the latter on overload to permit its displacement under the effort exerted thereon by the frame under the stress of the spring energizing the circuit opener.

6. In a circuit breaker, a pivoted frame, a manually operated circuit opener pivoted thereon, a spring stressing said circuit opener against the frame, a displaceable member normally supporting the frame, a warping U-shaped thermostat normally engaging said displaceable member but freeing the latter on overload to permit its displacement under the effort exerted thereon by the frame under the stress of the spring energizing the circuit opener.

7. In a circuit breaker, a pivoted frame, a pivoted latch arm having a supporting shoulder adjacent its pivot for the engagement of said frame thereon, and a latching nose at a point remote from the pivot, a warping thermostat normally engaging said latching nose to maintain the latch in frame-supporting position, together with a circuit opener pivoted on the frame, and a spring interposed between the circuit opener and frame and stressing the latter against the latch.

In testimony whereof I have signed my name to this specification.

CARL ERIC ANDERSON.
